(57) **CLAIM**

The ornamental design for a retracting extension cord reel, as shown and described.

DESCRIPTION

FIG. 1 is a perspective view of a retracting extension cord reel incorporating our new design, having an electrical extension cord disposed therein;

FIG. 2 is a front view of the retracting extension cord reel illustrated in FIG. 1;

FIG. 3 is a rear view thereof;

FIG. 4 is a top plan view thereof;

FIG. 5 is a bottom plan view thereof;

FIG. 6 is a right side elevational view thereof; and,

FIG. 7 is a left side elevational view thereof.

The ornamental design which is claimed is shown in solid lines in the drawings. The broken lines in the drawings are for illustrative purposes only and form no part of the claimed design.
